CHLORINATION OF PARAFFINIC
HYDROCARBONS

Everett Gorin, Dallas, Tex., assignor, by mesne assignments, to Socony-Vacuum Oil Company, Incorporated, New York, N. Y., a corporation of New York

Application January 26, 1946, Serial No. 643,800

10 Claims. (Cl. 260—659)

1

This invention relates to a process for the chlorination of normally gaseous hydrocarbons. The invention is concerned particularly with the production of chlorides of methane from methane and dry natural gas, i. e., a natural gas from which most of the ethane and substantially all of the propane and higher molecular weight hydrocarbons have been removed.

Vast quantities of methane are available in the form of natural gas, the chief use of which has been its utilization as a fuel. A considerable amount of the supply is used to produce carbon black. More recently attempts have been made to increase the production of fuels for internal combustion engines by converting methane to normally liquid hydrocarbons in such synthetic processes as the Fischer process and modifications of this process and new processes have been proposed for using methane as a starting material for the production of chemical intermediates by oxidation and chlorination processes.

Various methods have been proposed for the chlorination of normally gaseous hydrocarbons, such as methane, to form therefrom the corresponding alkyl and alkylene chlorides. The conventional method of direct chlorination with free chlorine has been used for many years. However, this method has several disadvantages which have not been entirely overcome. The reaction of free chlorine with methane is highly exothermic and hence the reaction is very difficult to control at moderate temperatures and explosive mixtures of the reactant gases are difficult to avoid. Also large volumes of hydrogen chloride are formed in the direct chlorination process and since the reutilization of the hydrogen chloride in the chlorination process is of primary importance to make any hydrocarbon chlorination process economically feasible, it becomes necessary to incorporate with the process a coordinating chlorine recovery process such as the Deacon process.

The primary object of this invention is to produce chlorides of methane. Another object of the invention is to provide a continuous process for the chlorination of methane and natural gas wherein the chlorination reaction is readily controlled. Another object of the invention is to provide a continuous process for the chlorination of methane and natural gas wherein the hydrogen chloride produced by such chlorination is utilized in producing chlorinating agent for the process. A further object of the invention is to provide a continuous vapor phase process for the chlorination of methane and natural gas

5 wherein explosive mixtures of free chlorine and the hydrocarbons undergoing chlorination are avoided. Other objects of the invention will appear hereinafter.

I have found that mercuric chloride may be reacted in the vapor phase with methane and natural gas to produce monochlorides and higher chlorinated derivatives of these gaseous hydrocarbons. The reaction of mercuric chloride with methane may be represented by the equation

The above reaction takes place at temperatures in excess of about 500° C. At temperatures above about 650° C. the chlorinated methane undergoes substantial decomposition to form olefins, aromatics, and hydrogen chloride even at relatively short contact times. I have found that alkyl chlorides such as ethyl chloride and propyl chloride cannot be produced with mercuric chloride in substantial yield by the chlorination of ethane and propane respectively. Ethylene and propylene are formed instead of the corresponding hydrocarbon chlorides. The natural gas used in my process must therefore contain only a limited amount of higher hydrocarbon, that is, preferably less than 15 mole percent of ethane and not more than 2 or 3 mole percent of propane. The conversion of normally gaseous hydrocarbons to aromatics at temperatures above 600° C. in the presence of volatile metallic chlorides, such as mercuric chloride, is taught and claimed in my copending application entitled Conversion of normally gaseous hydrocarbons, Serial Number 400,296, filed June 28, 1941, now U. S. Patent 2,396,697. In converting mixtures of mercuric chloride and normally gaseous hydrocarbons to aromatics, the mercuric chloride is completely reduced to mercury in the chlorination-dehydrochlorination process.

45 I prefer to operate the herein described process of converting methane to chlorinated methane at temperatures within the range of from about 525° C. to about 575° C. under conditions of contact time described hereinbelow such that no more than 90 percent of the mercuric chloride is reduced to mercury and only minor amounts of the chlorinated hydrocarbon is reconverted to hydrocarbons. I have found that if contact times 50 substantially greater than those required to reduce about 90 percent of the mercuric chloride are employed the ultimate product consists primarily of hydrocarbons and not chlorinated methane. If contact times below those required to obtain about 35 percent reduction of the mer-

2

curic chloride are employed the concentration of chloromethanes in the product gas is too low to permit their economical recovery. I have observed that when contact times within the range of from

$$0.5 \times 10 \left(\frac{10950}{T} - 11.91 \right)$$

to

$$5.0 \times 10 \left(\frac{10950}{T} - 11.91 \right)$$

seconds are employed, 35 percent to 90 percent of the mercuric chloride is reduced. In the above expression T is the degrees Kelvin maintained in the reaction zone. Thus, for operation at a temperature of 525° C. the proper range of contact time is from about 32 seconds to about 322 seconds and for operation at 575° C. the range of contact time is from about 5 seconds to about 50 seconds, that is, an overall range of contact time of from about 5 seconds to 322 seconds for my preferred operating temperatures. The term contact time as used in this specification and in the claims is defined as the reciprocal space velocity and is equal to the total volume of the reaction zone free space divided by the volume of reactant gases, reduced to standard conditions of temperature and pressure, passed therethrough per second. Contact time of the reactant gases in the chlorination zone as defined hereinabove is greatly reduced when operating at elevated pressures. The chlorination reaction may be carried out at pressures from atmospheric to about 200 pounds gage, preferably about 150 pounds gage. However, the pressures are in all cases maintained sufficiently low so that the reaction is carried out under vapor phase conditions.

The endothermic reaction of mercuric chloride with methane to form methyl chloride is of particular utility since the by-product mercury and hydrogen chloride can be reacted in the presence of oxygen or oxygen containing gases to reform mercuric chloride chlorinating agent. This reaction is exothermic and furnishes an excess of heat over that required to chlorinate methane with the mercuric chloride agent. The reaction of mercury with hydrogen chloride and atmospheric oxygen to form mercurous chloride takes place at temperatures from about 50° C. to about 250° C. according to the equation

The mercurous chloride dissociates to produce free mercury and mercuric chloride at a temperature of about 250° C. or above. The reaction between mercury, hydrogen chloride and oxygen may be carried out at temperatures above 250° C. to form mercuric chloride directly according to the equation

In my process I prefer to regenerate mercuric chloride under conditions of temperature and pressure approximating temperature and pressure conditions in the chlorination zone.

The process of chlorinating methane by means of mercuric chloride may be carried out either batchwise or as a continuous process. Thus, by the use of a multiplicity of towers packed with material having a high specific heat, that is, high heat capacity, the heat produced in the regeneration of mercuric chloride may be stored in the packing and by successively alternating the chlorination and regeneration reactions in these towers a part of the heat of regeneration may be

most efficiently utilized in the chlorination process. Such a continuous regeneration method which is coordinated with a process for chlorinating methane or hydrocarbon mixtures consisting essentially of methane with only a minor amount of ethane is described hereinbelow. These mixtures which may be chlorinated by my process are obtained from a dry natural gas from which substantially all of the hydrocarbons having more than two carbon atoms per molecule have been removed.

Referring to the drawing, towers 1 and 2 are used alternately as methane chlorination zones and regeneration zones. These towers are packed with suitable refractory, high heat capacity material, which is inert to the chlorination reactants and regeneration reactants. The packing material should also have the property of relatively high thermal conductivity in order that the heat stored in the regeneration cycle be delivered readily to the reactant gases in the chlorination cycle. Suitable materials are quartz and relatively non-porous carborundum. The packing may be disposed in a series of beds as indicated or the packing may be continuous in the towers. Towers 3 and 4 which are used to recover residual mercuric chloride vapors and mercury from the gaseous effluent of the chlorination cycle are also packed with inert packing having the above properties.

The packing in these towers should be relatively porous in order to adsorb the mercuric chloride and hence I prefer to use porous packing such as porous carborundum or crushed fire brick in towers 3 and 4.

35 Methane in line 10 is passed by means of compressor 11 through coil 12 in furnace 13 at a pressure of about 150 pounds per square inch. Molten mercuric chloride in line 16 is passed by means of pump 17 to coil 18 in furnace 13. In 40 furnace 13 the streams of methane and mercuric chloride are raised to a temperature within the range of from about 525° C. to about 575° C. Vaporized mercuric chloride in line 20 passes to methane line 21 and the mixed vapors pass 45 to manifold line 22 which leads to reactor 1. Valves 23 and 24 in line 22 are maintained in the open position to permit free passage of the gas to reactor 1 while valve 25 in line 26 and valve 27 in line 28 are closed as is also valve 29 in line 22.

The mole ratio of methane to mercuric chloride introduced to reactor 1 should be within the range of from about three to one to about ten to one. An excess of methane is preferable in order 55 to obtain maximum conversion of mercuric chloride to methyl chloride product and minimum formation of the higher chlorinated derivatives of methane. A high ratio of methane to mercuric chloride also prevents the condensation of the 60 mercuric chloride and mercury product vapors. As the mixed vapors pass upward in tower 1 they contact the hot packing material which has been heated in a previous regeneration cycle and the reaction indicated by (1) produces a gaseous 65 mixture consisting of chlorinated methane, unreacted methane, hydrogen chloride, vaporized metallic mercury and unreacted mercuric chloride vapor. With valves 35 and 36 in line 37 in the open position and valves 38, 39, and 40 in lines 70 41, 42, and 43 respectively closed, the vapor product passes overhead through line 44 to condenser 45. In condenser 45 the mercury and unreacted mercuric chloride vapors are condensed and the 75 mixed product of non-condensed product gases and liquid mercury and mercuric chloride passes

through line 46 to hot settler 47. Settler 47 is operated at a temperature of from about 275° C. to 300° C. and at a pressure substantially the same as reactor 4, that is, about 150 pounds gage, and the metallic mercury and liquid mercuric chloride settle therein to form two liquid layers, the liquid mercuric chloride being supported by the liquid mercury. The liquid mercuric chloride is recycled to furnace 13 through line 48. Liquid mercury is withdrawn from settler 47 through line 49 and transferred to heater 50 by means of pump 51. The liquid mercury is vaporized in heater 50 and the vaporized mercury passes therefrom through line 52 to line 53 through which reactant gases for the regeneration of mercuric chloride pass to tower 2 described hereinbelow.

The gaseous effluent from settler 47 consisting of unreacted methane, chlorinated hydrogen chloride, and small amounts of mercuric chloride and mercury vapor pass overhead through valved line 60 to cooler 61 where the temperature of the gaseous mixture is lowered to the range of about 60° C. to 100° C. to condense out any residual mercuric chloride and mercury. The mixture is passed through line 62 to manifold line 63 and thence by line 64 to packed tower 3, valve 65 in line 64 being in the open position. Valve 67 in line 68 and valve 71 in line 72 are closed in order to isolate tower 3 from gaseous stream passing to tower 4. In tower 3 suspended solid mercuric chloride is deposited on the packing. With valves 75 and 77 in lines 78 and 80 respectively closed, and valve 81 in line 82 open the mixture of product gases and a small amount of mercury pass through line 84 which leads to liquid mercury sump 85 from the bottom of which any residual mercury is passed through line 86 to line 49. The gaseous product passes overhead from sump 85 through valved line 87 to absorber 90.

In absorber 90 the gaseous product mixture is contacted countercurrently with a stream of hydrogen chloride-water azeotrope containing from 20 to 25 percent hydrogen chloride introduced to absorber 90 through line 91 by means of pump 92. The absorber is operated at pressures in excess of 100 pounds gage and the azeotrope removes hydrogen chloride from the gaseous mixture. The solubility of methyl chloride and other chlorinated methanes in the azeotrope is slight compared with that of hydrogen chloride and the azeotrope rapidly becomes saturated with the hydrocarbon chlorides after which further absorption of the hydrocarbon chloride product practically ceases. The hydrogen chloride enriched azeotrope passes from the bottom of absorber 90 through valve 93 in line 94 to fractionating tower 95 which is equipped with heating means 95 and top cooling means 97. Hydrogen chloride passes overhead from fractionator 95 to the regeneration zone 2 through line 98 which leads to line 53. If desired, the hydrogen chloride may be scrubbed with sulfuric acid to remove any water vapor before recycle to tower 2. Hydrogen chloride from an external source is introduced to line 53 through line 99. Lean azeotrope passes from the bottom of fractionator 95 through line 100 to cooler 101 and thence through line 102 to line 91 for reuse in absorbing hydrogen chloride from the product gas.

The gaseous product from absorber 90 consisting essentially of unreacted methane and chlorinated methane passes overhead through line 105 to absorber 106 wherein the gas is contacted countercurrently with a suitable solvent for the

chlorinated hydrocarbon such as a petroleum naphtha fraction. A relatively high boiling, narrow cut kerosene fraction or mineral seal oil may be used or a chlorinated hydrocarbon such as carbon tetrachloride may be used as the absorbent liquid introduced to absorber 106 through line 107 by means of pump 108. Absorber 106 is operated at pressures in excess of 100 pounds per square inch gage and as the absorbent descends in the tower the chlorinated methane is absorbed from the product gas stream. If desired, towers 106 and 90 may be packed with suitable inert packing in order to obtain more efficient contact of the gas with the liquid absorbent. Unabsorbed methane passes overhead from absorber 106 through recycle line 109 which joins methane feed line 10. The chlorinated methane enriched absorbent is withdrawn from absorber 106 through line 110 and passes through valve 111 to fractionator 112 which is equipped with bottom heating means 113 and top cooling means 114. Lean absorbent is withdrawn from fractionator 112 through bottom drawoff line 115 and passes via cooler 116 and line 117 to absorbent feed line 107. Chlorinated methane passes overhead from fractionator 112 through line 118. If desired, the chlorinated product may be withdrawn as a side stream from fractionator 112 (not shown) reserving top drawoff line 118 for the elimination from the product of any trace of methane picked up by the absorbent in absorber 106 when operating the same at high pressure.

The regeneration of mercuric chloride reagent by means of mercury, oxygen, and hydrogen chloride according to Equation 3 above is accomplished in tower 2 while tower 4 is in operation on the chlorination cycle as described hereinabove. Reaction tower 2 after being withdrawn from the chlorination cycle must be purged of hydrocarbon gases before inauguration of the regeneration cycle. With valve 120 in line 28 and valve 121 in line 42 open and valves 122 and 123 in lines 22 and 43 respectively closed, reactor 2 is purged by means of hot flue gas introduced to the reactor through lines 124, 28, and 22, and the purge gas passes from reactor 2 through lines 43, 42, and 125. Following the purging of tower 2 valves 120 and 121 are closed, valves 122 and 123 are opened and valves 126 and 127 in lines 26 and 41 respectively are set in the open position, thus preparing the inlet and outlet manifold lines to reactor 2 for the regeneration cycle which is described below.

Following the deposition of solid mercuric chloride on the packing in tower 4 the recovery of the solid mercuric chloride is accomplished in the following manner. Valve 132 in line 72 and valve 133 in line 78 are opened. Valve 134 in line 135 which connects with hot methane feed line 21 is now opened and part of the hot methane from furnace 13 is passed through lines 135, 72, and 68 and thence through tower 4 and lines 80, 78, and 136 back to furnace feed line 10. The hot methane vaporizes the mercuric chloride and carries the vapors back to the chlorination cycle. The extent to which the packing is raised in temperature by the hot methane purge will depend on the length of time necessary to remove the deposited mercuric chloride. Since the amount of mercuric chloride deposited is usually small, the duration of the hot methane purge will be relatively short. When it becomes necessary to continue the hot methane purge for sufficient time to heat the packing in tower 4 to a relatively

high temperature in order to vaporize substantially all of the mercuric chloride the heat stored in the packing in the heating step may be recovered and the temperature of the packing may be lowered to mercuric chloride adsorption temperatures by preheating cold methane passing to furnace 13. In order to lower the temperature of the packing, valve 134 in line 135 is closed and valve 138 in line 139 which leads from line 10 to line 135 is opened and relatively cold methane is passed through tower 4 until the packing reaches the desired low temperature. Valves 132, 133, 138, and 140 are then closed and valves 67 and 77 are opened to line up tower in preparation for the mercuric chloride adsorption cycle.

Referring now to the mercuric chloride regeneration cycle, a free oxygen containing gas such as air is introduced to the process through valved line 150 which connects with line 53. As indicated hereinabove, hydrogen chloride is introduced to line 53 through lines 98 and 99 and mercury is introduced to line 53 from line 49. Makeup mercury is introduced to line 49 through line 151. If desired, the mixture of air, hydrogen chloride, and mercury vapor in line 53 may be raised in temperature by passing the mixture in heat exchange with the overhead product from reactor 1 in line 44. The amount of preheat given to this mixture will depend on heat losses from regeneration reactor 2. In any case the temperature of the mixture as it enters reactor 2 is sufficiently high to avoid condensation of mercury vapors from the mixture. The proportion of oxygen and mercury in the mixture should be such that at least one mole of oxygen and two atoms of mercury are furnished respectively for each four moles of hydrogen chloride. I prefer to use at least 10 percent excess of mercury over that required by stoichiometric proportions as indicated by Equation 3 above in order that the hydrogen chloride may be substantially completely oxidized.

The gaseous mixture from line 53 is passed by compressor 152 through lines 153, 41, and 43 to reactor 2 at a pressure within the range of from atmospheric to about 200 pounds per square inch, preferably about 150 pounds per square inch. The temperature, which increases in reactor 2 due to the exothermic nature of the reaction, is maintained within the range of from about 500° C. to about 650° C.

The reaction product from regeneration reactor 2 passes through valve 122 in line 22 and through valve 126 in line 26 to line 154 leading to condenser 155 where the temperature is lowered to the range of from about 275° C. to 290° C. or 300° C., and the mixture of liquid mercuric chloride, water vapor, oxygen depleted air, and unreacted mercury passes through line 156 to the mercuric chloride recovery zone. In the mercuric chloride recovery zone the mixture is introduced to a settler similar in operation to settler 47 from which liquid mercuric chloride is passed by line 160 to line 48 and thence to mercuric chloride feed line 16 leading to furnace 13. Liquid mercury is recycled from the settler in the mercuric chloride recovery zone through line 161 to line 86 which leads to mercury recycle line 49. Mercuric chloride, hydrogen chloride, and mercury in the off gas from the settler may be recovered by cooling the gas to about 100° C. and passing the cooled gases through a packed tower such as tower 3 described above or the gas may be cooled to a lower temperature and scrubbed with water to absorb the mercuric chloride. The water solution may then be concentrated and

evaporated and the recovered mercuric chloride is returned to the chlorination cycle. The mercury recovered from the cooled gas is returned to the regeneration cycle.

The following example illustrates the chlorination step of my process.

A gaseous mixture consisting of methane and vaporized mercuric chloride in the mole ratio of about five moles of methane per mole of mercuric chloride was passed through a Pyrex glass tube at a temperature of 530° C. for a contact time of 55 seconds. Under these conditions 47.6% of the mercuric chloride was reduced to metallic mercury and about 9.0 percent of the methane was chlorinated. The yield of chloromethanes based on the quantity of methane and mercuric chloride reacted was quantitative. The chlorinated product consisted of 87.3 percent methyl chloride and 12.7 percent methylene chloride.

20 My invention makes possible a method for chlorinating methane or natural gas rich in methane wherein temperature conditions are easily controlled and the process makes possible chlorination of these gases without danger of creating an explosive mixture of hydrocarbon and chlorine. The process also makes possible the reutilization of hydrogen chloride formed in the chlorination process.

25 While I have described one method whereby my invention may be practiced, the invention should not be limited to the specific mode of operation described since many variations will occur to those skilled in the art.

I claim:

30 1. The process for the manufacture of at least one chloride of methane from methane which comprises maintaining said methane in contact with a chlorinating agent consisting of mercuric chloride vapor in a reaction zone at a temperature within the range of from about 500° C. to about 650° C. and for a contact time such that not more than 90 percent of said mercuric chloride is converted to metallic mercury and recovering said chloride of methane from the gaseous effluent of said reaction zone.

35 2. The process for the manufacture of a chlorinated hydrocarbon which comprises passing a hydrocarbon gas stream consisting essentially of paraffinic hydrocarbons of not more than two

40 carbon atoms and comprising not more than 15 mole percent of ethane in contact with mercuric chloride vapor in a reaction zone at a temperature within the range of from 500° C. to 650° C. for sufficient time to convert at least 35 percent and 45 not more than 90 percent of said mercuric chloride to free mercury whereby at least a part of said hydrocarbon is chlorinated and hydrogen chloride is formed and recovering said chlorinated hydrocarbon from the gaseous effluent of said reaction zone.

50 3. The process for the manufacture of a chlorinated hydrocarbon which comprises passing a hydrocarbon gas stream consisting essentially of paraffinic hydrocarbons of not more than two carbon atoms and comprising not more than 15 mole percent of ethane in contact with mercuric chloride vapor in a reaction zone at a temperature within the range of from about 500° C. to about 650° C., adjusting the contact time of said gas with the mercuric chloride vapor in said reaction zone to a number of seconds greater than represented by the expression

$$\text{Contact time} = 0.5 \times 10 \left(\frac{10950}{T} - 11.91 \right)$$

and less than that represented by the expression

$$\text{Contact time} = 5.0 \times 10 \left(\frac{10950}{T} - 11.91 \right)$$

where T is the temperature in degrees Kelvin in said reaction zone, and recovering said chlorinated hydrocarbon from the gaseous effluent of said reaction zone.

4. The process for the manufacture of chloromethanes which comprises passing a gaseous mixture of methane and mercuric chloride through a reaction zone at a temperature within the range of from about 500° C. to about 650° C. at a rate such that the contact time is sufficient to reduce at least 35 percent and not more than 90 percent of said mercuric chloride to free mercury, cooling the gaseous effluent from the reaction zone to a temperature below 500° C. and sufficient to condense mercuric chloride and metallic mercury therefrom, and recovering the chloromethane product.

5. The process for the manufacture of methyl chloride from methane and mercuric chloride which comprises the steps of (1) introducing a gaseous mixture consisting essentially of methane and mercuric chloride to a chlorination zone at a temperature within the range of from about 525° C. to about 575° C. whereby at least a part of said methane is converted to methyl chloride and hydrogen chloride and at least 35 percent of said mercuric chloride and not more than 90 percent of said mercuric chloride is reduced to free mercury, (2) fractionating the reaction product of step 1 to obtain separate streams of unreacted methane, methyl chloride, hydrogen chloride, unreacted mercuric chloride, and free mercury, (3) passing the streams of free mercury and hydrogen chloride of step 2 and hydrogen chloride introduced from an external source in contact with a free oxygen containing gas in a separate reaction zone to regenerate mercuric chloride, (4) separating mercuric chloride from the reaction product of step 3, (5) recycling the unreacted methane and unreacted mercuric chloride of step 2 and the mercuric chloride of step 4 to the chlorination zone of step 1 of the process, and (6) recovering said methyl chloride from step 2 of the process.

6. The process as described in claim 5 wherein the gaseous mixture introduced to the chlorination zone contains at least three moles of methane per mole of mercuric chloride.

7. The process as described in claim 5 wherein the reaction zones of steps 1 and 3 consist of towers packed with refractory high heat capacity solid particles.

8. The continuous process for the manufacture of at least one chloromethane from methane which comprises the steps of (1) continuously passing a gaseous mixture of said methane and mercuric chloride through a reaction zone at a temperature within the range of from about 525° C. to about 575 C. at a contact time in seconds corresponding to the expression

$$\text{Contact time} > 0.5 \times 10 \left(\frac{10950}{T} - 11.91 \right)$$

and < than

$$5.0 \times 10 \left(\frac{10950}{T} - 11.91 \right)$$

where T is the temperature in degrees Kelvin maintained in said reaction zone to form a vapor mixture consisting essentially of unreacted methane, unreacted mercuric chloride, chlorinated methane, hydrogen chloride, and free mercury, (2) continuously fractionating the vapor mixture of step 1 to obtain separate streams consisting essentially of unreacted methane, unreacted mercuric chloride, chlorinated methane, hydrogen chloride, and free mercury, (3) continuously passing the hydrogen chloride and free mercury of step 2 in contact with a free oxygen containing gas in a separate regeneration zone whereby mercuric chloride is regenerated and water vapor is formed, (4) continuously separating the mercuric chloride from the water vapor of step 3, (5) recycling the unreacted methane and mercuric chloride of step 2 and the regenerated mercuric chloride of step 4 to step 1, and (6) recovering chlorinated methane from step 2 of the process.

9. The process for the manufacture of at least one chloride of methane from methane and mercuric chloride which comprises the steps of (1) passing a gaseous mixture consisting essentially of methane and mercuric chloride through a reaction zone packed with a refractory solid at a temperature within the range of from about 500° C. to about 650° C. whereby said methane is chlorinated and hydrogen chloride is formed and at least 35 percent of said mercuric chloride and not more than 90 percent of said mercuric chloride is reduced to free mercury, (2) fractionating the reaction product of step 1 to obtain separate streams of unreacted methane, at least one chloride of methane, hydrogen chloride, unreacted mercuric chloride, and free mercury, (3) passing the free mercury and hydrogen chloride of step 2 and hydrogen chloride introduced from an external source in contact with a free oxygen containing gas in a separate reaction zone packed with a refractory solid at a temperature within the range of from about 500° C. to about 650° C. to regenerate mercuric chloride whereby at least a part of the exothermic heat of the reaction is stored in the packing of said separate reaction zone, (4) separating mercuric chloride from the reaction product of step 3, (5) recycling the unreacted methane and unreacted mercuric chloride of step 2 and the mercuric chloride of step 4 to the reaction zone of step 1, and (6) recovering said chloride of methane from step 2 of the process.

10. The process as described in claim 9 wherein the processes of steps 1 and 3 are carried out alternately in the same reaction zone whereby at least a part of the heat stored in the reaction zone of step 3 is utilized in step 1 of the process.
